ABSTRACT

A mass-produced house designed to be nested and folded into a compact package for conveyance by one vehicle and unloadable therefrom as a nearly-completed house on the building site, and made of light but strong panels and floor bases, comprises a utility section having a floor base and including, in already-erected condition on the base, a long outer wall, a long inner wall, two shorter outer walls, and inner walls forming a kitchen, an adjacent bathroom, and an additional room adjacent the bathroom, and including necessary utilities. The package also includes a second section having a floor base and including, in already-erected condition on the base, a long wall and two shorter outer walls. The second section is designed to nest with the utility section with the shorter walls of both sections being disposed in overlying relation. The two sections are desirably hinged, and a third section may be added in nesting relation.

FIG. 24

HOUSING PACKAGE DESIGNED TO BE CONVEYED BY ONE VEHICLE

BACKGROUND OF THE INVENTION

At the present time, the home building industry is reaching an impasse due to rapidly accelerating costs of both materials and labor. To counteract these factors, there has been a trend toward greater use of prefabricated homes. Although such housing does substitute cheaper mechanized factory labor for on-site skilled labor, the construction of the separate building elements, as well as their transportation and erection have unfortunately been essentially the same as for the conventional expensive on-site construction.

There also has been a new trend toward the use and application of mobile homes. However, such homes have not served more than a stop-gap purpose to avoid the costs, because they do not adequately serve the purpose of a family home, both in appearance and in the availability of living space, as well as in the convenience of adequate utilities and storage space.

SUMMARY OF THE INVENTION

This invention deals with mass production of low cost housing having dimensional stability, and with the use of novel elements enabling the delivery on a conveyance to a proposed site, a complete house nested and folded into a compact package and so designed that it may be completely erected and ready for occupancy in a minimum of required man hours. The novel features include the construction, delivery and erection of the house.

More specifically, the invention relates to the continuous or semi-continuous production of housing components, their novel positioning and assembly on a truck, for example, and their removal and erection on the building site. By use of the present invention, it is possible to build, deliver and erect a 5-room (2-bedroom, 1 bathroom) house, including all utilities, by a few men and hoist in a single day at a cost of about one-third or less of the present cost of conventional homes.

The production involves a continuous or semi-continuous feeding of a corrosion-resistant rigid sheet forming the exterior wall of the building. After or before the sheet is cut to the desired length, it is passed between forming rolls for embossing a design which not only is decorative, but also serves as a rigidizing means. Thereafter, openings are punched out of the sheet, at predetermined locations, to accommodate windows, doors, to serve as vents, and the like.

After this step, metal studding is affixed to the inner surface of the wall sheet, and then a layer of plastic foam is adhered to the surface for insulating and sound-proofing. Thereafter, the pre-engineered and pre-manufactured plumbing manifold and wiring harnesses are attached, and the plastic layer is covered by a rigid interior wall panel which is affixed to the studding. Finally, the doors, windows, etc., are inserted into their corresponding openings and affixed to the wall, and the wall unit is ready for assembly or packing onto a truck or freight car.

The packing, assembly and delivery of the house also have many novel features. First of all, the utility section is completely built, except for the roof. This section consists of an already-assembled unit comprising a floor base around which are mounted four walls which

circumscribe a kitchen with its concomitant utilities, such as a washer, dryer, refrigerator, range, etc., an abutting bathroom having its built-in toilet and washing facilities, and an additional room, say a bedroom, connected to the bathroom, all of which rooms are equipped with the necessary inner walls, closets, shelving, etc. This suite of rooms may have a cathedral type ceiling, or it may be provided with a lower ceiling panel covering the entire section.

This transportable house also includes at least an additional floor base onto which the three walls of a second section (say a bedroom and an adjoining dining area adjacent the kitchen) are already erected. A wall opening is provided in the utility section, for example, to allow the second section to be nested and overlaid over the first section in a manner such that the floor base of the second section is disposed in overlying relation with respect to the inner wall of the first section.

If a 6-room house is desired, a third floor base for a third section is included, say as a living room area, and it is provided with an attachable outer wall. The third floor base is disposed in overlying relation with the long wall of the second section while its outer wall is in overlying relation with its floor base or with the outer wall of the utility section.

A novel hinging arrangement is provided for the floor sections as well as the outer wall of the third section so that the second or third sections may be nested with and folded over the utility section, making possible the transporting of this nearly-completed house by means of one truck or other conveyance. If the latter is a truck-trailer, the cab or trailer may also carry a hoist, as well as a compressor, generator, cement, tools, as well as the remaining structural elements needed to complete the house.

The three long walls of the 6-room house (two outer and one inner) are desirably slightly gabled in the center, and flat roof panels are disposed thereover at right angles to the long walls. Preferably, four panels are used, and the middle two panels are desirably hinged to form the central portion. In this package, there are stored in or over the utility section, wall portions of closets, built-in buffet, and other building elements.

When this nested and folded package is delivered to the building site, leveling beams having attached jacks (which may be mounted on the side of the conveyance) are laid out on the site, and elevated pilings are provided on which the house is to be placed. The package is slid off the conveyance onto the beams on the elevated jacks so that the beams are above the pilings. Then, the house is unwrapped in a process reverse to that already described for the packaging operation, and the house is lowered and anchored to the pilings, after which the beams and jacks are removed from under the house. Finally, the roof and remaining structural elements are removed from the conveyance and the completion of the erection of the house is undertaken.

It will be noted that, when the house of the present invention is removed from the truck and disposed over the building site, it is already at least over three-fourths completely erected by the use of semi-skilled factory work, and that most of the expense of the construction and erection of a conventional house has been eliminated.

BRIEF DESCRIPTION OF THE DRAWINGS

The invention will be more readily understood by reference to the accompanying drawings in which a preferred embodiment is described, and in which:

FIG. 1 shows a floor plan of a 6-room house made in accordance with the present invention;

FIG. 2 depicts a schematic perspective view in flow sheet form showing the steps in the manufacture of the floor bases;

FIG. 3 illustrates a similar flow sheet outlining the steps in the erection of the wall panels on the floor bases;

FIG. 4 presents a perspective view of a 6-room house of the present invention ready to be nested and folded for transportation to the building site;

FIG. 5 shows a schematic plan view of a modified type of house in nested condition for shipment;

FIG. 6 shows another modification of a nested house;

FIG. 7 depicts the house of FIG. 6 in unfolded form, except for one of the roof panels;

FIG. 8 illustrates a top view of portions of two floor bases connected in hinged relation, when in flat form;

FIG. 9 illustrates a front view of the connected portion of FIG. 8, when in folded condition;

FIG. 10 illustrates a cross-sectional view taken along the plane of line 10—10 in FIG. 9;

FIG. 11 presents a perspective view of the 6-room house of FIGS. 1 and 4 when packaged in nested and folded condition and mounted on a tractor-trailer with other building elements, ready for delivery to the building site;

FIG. 12 is a perspective view of the trailer portion of FIG. 11 without the packaged house and showing the leveling beams, drilling auger and piling details for the unloading operation;

FIG. 13 shows a view similar to that in FIG. 12, but with the house package being unloaded on the leveling beams;

FIG. 14 is a perspective view of the house package ready to be unfolded on the leveling beams;

FIG. 15 is a similar view as in FIG. 14, but with the second section of the house in unfolded condition on the leveling beams;

FIG. 16 shows a perspective view of the entire house as unloaded and unfolded with the leveling beams about to be removed;

FIG. 17 is a perspective view of the house of FIG. 16, with leveling beams removed and additional building elements (except roof) built on;

FIGS. 18 and 19 are perspective side and elevational side views, respectively, of a leveling beam-jack combination in which the jack is concealed in the beam;

FIG. 20 depicts a perspective view of the mounting of a leveling beam and the pusher element on the trailer;

FIG. 21 shows a side elevational view, partly in cross-section of a screw support in a piling in the position of supporting the end of a house, with a portion of the house support plate cut away to reveal the locking means;

FIG. 22 is a cross-sectional end view of the packaged house taken along the plane of line 22—22 in FIG. 11;

FIG. 23 is a cross-sectional end view of a portion of the roof of the house of the present invention, and

FIG. 24 depicts a rear perspective view of the house of FIGS. 1 and 4 when in final condition ready for occupancy.

The same numerals refer to the same or similar parts.

DESCRIPTION OF THE PREFERRED EMBODIMENTS

The house of the present invention is made up essentially of light weight but strong panels and bases. The basic unit is the utility section indicated generally by numeral 50 in the floor plan shown in FIG. 1. Before being placed on the conveyance, this section has, in already-erected condition, floor base 51, long outer wall 52, shorter outer walls 53 and 54, and inner wall 55. It also has the necessary utilities and inner walls forming the kitchen, the bathroom, and another room adjacent to the bathroom, such as a bedroom. Details of these and other features will be discussed later.

The house also has a second section, such as the section indicated generally by numeral 79 which, before it is placed on the conveyance, also has floor base 80 and, in already-erected condition on said base, a long wall 86 and two shorter outer walls 82 and 83. The said two sections are considered as the basic group and, if used as a 5-room house, wall 86 would be an outer wall and the second section 79 may be a combined dining area and bedroom, for example, thus making up the house.

In the event a 6-room house is desired, wall 86 is made as an inner wall and the third section, indicated generally by numeral 90, is attachable to the second section. Before being placed on the conveyance, the third section 90 is provided with a floor base 91. Long outer wall 93 may be attached at its base, in hinged relation, as will be outlined later.

The manufacture of the floor bases may be effected in the manner outlined in FIG. 2. Conveyor 118 may be employed for permitting building thereon of the utility section floor base 51, for example. Metal channel frame members 195 serve as the perimeter of the base and metal or wooden joists 201 have their ends attached in these frame members. The next step is to attach sub-floor 197" to the wooden joists, and the floor base is rotated by a device, such as that indicated generally as 300, and the bottom of the sub-floor (which may be made of plywood) is sprayed with an insulating layer of plastic foam. Finally, the floor base is rotated again and deposited on conveyor 213. Piping and other utility elements are installed in the floor base prior to the foam application.

Conveyor 115 similarly enables production thereon of floor base 91 of the third section, while conveyor 203 similarly permits production of floor base 80. Indicated generally by numeral 204 is a modified means for rotating floor base 80 into position with the other bases. Base 80 is moved into frame 205 and is held between channel members 206 and 207 which are attached to rings 208 and 209. A motor (not shown) then turns the rings via pinions 210 until base 80 is reversed, and then the conveyor moves it into position with bases 51 and 91. Meanwhile, conveyor 211 moves the utility elements, bath fixtures, closets, etc., indicated generally as 212, and these are installed on the particular floor base to which they are assigned. Thereafter, con-

veyor 213 transports the bases for receiving the wall panels which are erected on the bases before the house is placed on the truck or other conveyance.

One manner of erecting the wall panels on the floor bases is depicted in FIG. 3. When conveyor 213 transports floor bases 51, 80 and 91 to the next station, overhead conveyor 214 transports the walls and other panels 93, etc., for erection on bases 91 and 80, for example, while conveyor 215 serves to transport walls 52, etc., for erection onto floor base 51. Thereafter, the almost completely erected house is transported by conveyor 213 for nesting and loading onto the conveyance.

A typical 6-room house made in accordance with this invention is depicted in the floor plan in FIG. 1. The utility section designated as 50, is provided with a floor base 51 (which may be 37 feet $\times$ 10 feet 10 inches), a long outer wall 52, shorter outer walls 53 and 54, and a long inner wall 55. Inner wall 56 defines a kitchen (say, 12 feet 5 $\frac{1}{2}$ inches long) which may contain a dryer 57, washer 58, range 59 and refrigerator 60. A portion 61 of the room extends beyond the rest of the house, and an outer wall portion 62 is designed to be installed at the erection site.

Inner walls 63 and 64 form a bathroom enclosure (say 7 feet 11 inches long) in which may be mounted a fiberglass tub 65, toilet 66 and sink 67. A linen closet 68 may also contain the water heater 69. The remaining space forms another room, say a bedroom 70 (say, 13 feet $\times$ 10 feet 1 $\frac{1}{2}$ inches), provided with a closet 71. Entrance door 72, and windows 73, 74, 75 and 76 are all mounted in place. Openings 77 and 78 serve as doors to the next (second) section, indicated generally as 79.

The second section also has a floor base 80 (say, 32 feet 11 inches $\times$ 10 feet 8 $\frac{1}{2}$ inches) disposed in abutting relation at 81 with the floor base of the utility section 50. This second section has two outer short walls 82 and 83 erected on base 80, as well as mounted windows 84 and 85. A long wall 86 is also disposed in erected position on floor base 80. A small section 96 of an outer wall, serving as a continuation of long inner wall 55, is installed in the open space 96' after the house is erected on the building site.

Wall 86 would necessarily be an outer wall (with proper windows mounted therein) if the house were sold as a 5-room house. However, in the present case of a 6-room house, wall 86 is an inner wall, and a wide opening 87 is provided as an access door to the dining area 88, which may also be entered through kitchen door 77. Space 89 may serve as a second bedroom. Opening 87 also serves as an access door to the third section.

The third section, indicated generally as 90, also has a floor base 91 (say, 31 feet 11 inches $\times$ 11 feet 4 $\frac{1}{2}$ inches) disposed in abutting relation at 92 to floor base 80 of the second section. The third section may be used as a living room. A long outer wall 93, having windows 94 and 95 installed therein is also provided, and it may be attached to the house before transportation to the site, as will be explained hereafter.

Walls 52, 55, and 86 are desirably provided with a central gable the peak being, say, 10 feet 5 inches from the floor. As shown in FIG. 4, gable 97 on wall 52, gable 98 on wall 53 and gable 99 on wall 93 serve to hold the flat roof panels after the house has been placed on the site.

The house, when ready for loading or when removed from the conveyance and unfolded, resembles the structure shown in FIG. 4. As already indicated, if the house were a 5-room house, floor base 91 and outer wall 93 would not be present, and long wall 86 would be in the form of an outer wall. A plenum chamber 100 may be provided over a portion of the utility section 50 for air conditioning equipment, if desired.

As is apparent from FIG. 4, the 6-room house of the present invention may be nested and folded into a compact package suitable to be transported by a truck or tractor-trailer, and then unfolded on site. The second section 79 may be turned with abutment 81 as a pivot, so that wall 84 will enter opening 61 and lie on its side edge 101 on floor base 51 of the utility section 50, so that walls 53 and 84 will be disposed in overlying relation. Likewise, wall 83 will cover wall 54 and edge 102 of wall 83 will lie somewhat parallel to the edge of floor base 51 outside of the building, while wall 86 will be disposed over the utility section 50. Thereafter, floor base 91 of section 90 would be disposed on top of wall 86 and wall 93 may be placed thereon or alongside of the package.

One of the novel features of the present invention is the hinging of the floor bases and other elements of the house to facilitate nesting and folding thereof into a compact package easily transportable to the building site. For example, floor base 51 of the utility section 50 may be hinged at hinges 103, 104, 105, and 106 to the floor base 80 of the second section. Likewise, floor base 80 of the latter section may be hinged at hinges 107, 108, 109, and 110 to floor base 91 of the third section, to facilitate the folding operation already outlined. Also, base 91 of the third section may be hinged at hinges 111, 112, 113, and 114 to the edge of long outer wall 93 (FIG. 4), thereby enabling wall 93 to be folded over base 91 before said base is raised in folding position. Or, it may be used to overlie wall 52 when it is in open position with respect to floor base 91.

Although the folding arrangement of the house shown in FIG. 4 is most desirable, the arrangement shown diagrammatically in FIG. 5 is an alternate for achieving a compact package. Here, the second section 79 is longer than the utility section 50 and both of the shorter outer walls 84' and 83 overlie, on the outside of the building, the shorter walls 53 and 54, respectively, of the utility section. The floor base and long wall of section 79 are not shown in this figure.

Another modification of a nested house of the present invention is depicted in FIGS. 6 and 7. In FIG. 6, the utility section 50 is disposed on floor base 80 in nested relation with the second section of the house (79). After the house is unloaded on the building site, wall 61' and other elements needed to complete the house are erected and roof panel 216 is removed from roof panel 217 and it is disposed over section 79, as will be outlined further (FIG. 7).

One type of hinging element 103 found suitable for effecting the folding operation is depicted in FIGS. 8, 9 and 10. Channel frame member 195' of floor base 80 is shown in flat condition in FIG. 8 with respect to channel member 195 of floor base 51. In FIGS. 9 and 10, these frame members are shown in folded condition (as in FIG. 11). The ends of joists 201 of floor base 51 are attached to channel members 195 which are in abutting relation to channel members 195' (of floor base 80) to which are attached joists 201'. The hinging

element comprises a metal U-shaped member 119, the free ends or prongs 121 of which are welded at 122 to the upper side of channel 195', with the curved end 123 of the U-member projecting out of top 120 of channel 195' and into channel 195. This is effected by leading prongs 121 of the U-member through holes 125 and 126 in the side of channel member 195. A strip of metal 124 between the holes serves to engage the U-member which straddles this strip and prevents U-member 119 from slipping out of channel member 195. Holes 125 and 126 allow room for movement of the channels clear of the U-member when folding is effected, using the U-member as a pivot.

When the house of, say the 6-room house of FIG. 4, is ready for conveyance to the site, it is nested and folded. Section 79 is turned with abutment 103 (FIG. 1) as the pivot, so that wall 84 enters opening 61 and lies on its side edge on floor base 51, and wall 86 is disposed on top of utility section 50. Then, floor base 91 is disposed on wall 86 and wall 93 may be placed under base 91 or at one of the sides or on top of the package. Other building elements needed to complete the structure are also provided and placed on the conveyance and in or on top of the utility section.

When in nested and folded condition and placed on the truck, the house of FIGS. 1 and 4 resembles the package indicated generally by numeral 127 in FIG. 11. The truck 128 carries on its cab portion a crane or hoist 129 which may be powered by the truck engine. The trailer portion 130 connected to truck cab 128 also is designed to carry the roof panels 131 on its forward portion, as well as a compressor and generator 132, a concrete mixer 133, and a storage bin 135 for the auger and other erection tools. Roof beams, odd panels 134, and attaching tools and other equipment may be stored on floor base 51 of the utility section 50 in space 61 (FIG. 1).

FIGS. 12-18 describe how the house is unloaded and erected on the site. Disposed below the house, and attached to the side of trailer 130 are at least a pair of jack screws 135 and 136. Leveling beams 137 and 138 are attached at one end to each jack screw in screw-engaging relation in a manner such that the ends of the beams may be lowered by turning handles 139 and 140, respectively, which are attached to the screws at the beam ends. The flat surface 141 of trailer 130 is provided with series of upwardly-projecting rollers 142 and 143, and the upper flat surfaces 144-145 of beams 137 and 138, respectively, are also provided with rollers 159 and 160.

A channel 146 is disposed over beam 137, in sliding relation therewith, and a sleeve 147 is mounted on channel 146 at right angles thereto. Rod 148, which slides in sleeve 147, has disposed on its end a vertical channel 149. Inside this latter channel, in engaging relation, rides the housing of motor 150. The motor is designed to drive auger 151. The other ends of beams 137 and 138 are supported by jacks 152 and 153.

The auger is used to drill holes 154 into which the concrete piling supports for the house are poured. Permanent forms 155 hold the concrete above the ground surface 226. Driven pushers 156 and 157 are provided for pushing the house package off the trailer and onto the beams.

While the concrete is still soft, and the beams are positioned above the tops of pilings 158, the pushers 156-157 push the house package 127 over rollers

142-143 and 159-160 until the floor base of the utility section 50 is in proper position over its supporting pilings, it being understood that auger 151 and its mountings are removed from the beam. Also, it is to be understood that the other pilings are also properly positioned to serve as supports for the other two floor bases 80 and 91 as they are unfolded from the trailer.

As shown in FIG. 13, house package 127 is positioned on leveling beams 137-138, with the J-hooks 161, 162, 163, 164, etc., in position over the soft concrete pilings for the anchoring operation. Thereafter, jacks 135-136 and 152-153 are used to lower package 127 until the J-hooks are buried in the concrete pilings 158, and the utility section is in proper position for permanent placement, as in FIG. 14.

Hoist 129 then is employed to raise the end of floor base 91 and to move it (with its attached wall 93 and floor base 80 of the second section) until their J-hooks 165-166, etc., are embedded in their respective pilings 158 and floor bases 80 and 91 are positioned over the pilings for permanent placement (using jacks 152', 153'', etc.) for support.

In FIG. 15, both the utility section 50 and the second section 79 are shown with J-hooks in place, and floor base 91 of the third section with J-hooks 171-172-173, etc., ready to be lowered into the final pilings 158 for anchoring. In FIG. 16, the house is placed in permanent position on all the pilings, and wall 93 is held vertically in place by hoist 129 until wall panels 174 and 175 (FIG. 1) are positioned and erected in place to complete the walls of the third section 90. Thereafter, the wall panels for spaces 61 and 96' are erected and the desired closets, buffets, or other structural elements for sections 79 and 90 are installed, and the roof panels 131 are mounted over gabled walls 52, 55, 92 and 93.

When the concrete in forms 155 is set enough to support the house load, jacks 135, 152, 136, 153, etc., are lowered and leveling beams 137 and 138 are pulled out from under the house. Thereafter, the remaining structural elements, such as exterior walls 62 and 174, as well as interior walls 218 and panel 96 are erected, as indicated by the solid lines in FIG. 17. The broken lines indicate the portion of the building which was delivered in already-erected condition on the site. Roof rafters 219 also are mounted, at their ends, onto the upper wall channel members 220, as will be outlined further.

As shown in FIGS. 18 and 19, jacks 152, 153, etc., may be pivoted at their tops at 176 in the sides of channel beams 137 and 138 and, when lowered completely, may be disposed entirely within the channel 177 of beam 137, etc.

One method of lowering the leveling beams and pushing the package from trailer 130 is shown in FIG. 20. Rack 178 is pivoted at 179 to arm 180 attached to trailer 130. Pinion gear 181 disposed inside the end of beam 137 engages rack 178 and it may be turned by handle 139. The outer edge 182 of the rack mounting is T-shaped and it fits into a similarly-shaped slot 183 in which the rack end rides. Pusher 156 rides in slot 184 on trailer surface 141. It is attached to the end of cable 185 riding on pulley 186 and on larger pulley 187 disposed under the trailer. Crank 188 may be used to turn pulley 187. Since housing 190 of rack 178 is pivoted at 189, it is apparent that beam 137 may be swung

in the direction of the arrow to parallel the side of the trailer when it is not in use.

Although there are now means for controlling the setting time of concrete so as to enable a scheduled erection program, FIG. 21 shows one means which may be employed to position the house in place even when the concrete piling has not yet completely set, as well as to reduce the length of the leveling beams. After holes 154 (FIG. 12) have been drilled for the pilings, a screw support, indicated generally as 221, is inserted in the hole before the concrete is poured. Support 221 comprises a flat base 222 onto which is attached the lower end of hollow tube 223, the upper inner end 224 of which is threaded to accommodate screw 225 which is extended to project above piling 158. The ground level is indicated as 226.

At and below the juncture of floor base channel frame members 195, a plate 227 is attached having a hole through which fits upper end 228 of screw 225. Plate 227 rests on shoulder 229 of screw 225, and a lock pin 230 above the plate holds and serves to lock in place support 221 with respect to the house.

It is apparent that, by use of such supports, it is not necessary that leveling beams 137 and 138 (FIG. 14) be any longer than the length of the package, as shown in FIG. 14, since the other floor bases 80 and 91 may be laid directly on supports 221, the height of which may be adjusted by turning screws 225 with a wrench inserted within the space of channel members 195.

A vertical cross section of the package 127 shown in FIG. 14, but without the utilities and extraneous unattached elements (but shown as it would appear erected on pilings) is depicted in FIG. 22. It will be noted that outer wall 52 of the utility section 50 is made up of an outer wall metal sheet (which may be plastic-coated on the outside) 190, desirably embossed with a shingle or clapboard design, for example, and coated on the inside surface with a layer 191 of plastic foam, such as a polyurethane of sufficient thickness to serve as adequate insulation for the climate involved. Sheet 190 is attached to load-bearing metal studs 192. Attached to the inside of studs 192 is an interior wall board 193 which may be of composition board, sheet rock, or the like, and preferably coated on the inside with a decorative plastic coating.

The bottoms of studs 192 are received in a wall base channel 194, the latter being affixed to metal floor channel frame 195' of floor base 51 by a fastener 196. Floor base 51, like the other floor bases, comprises (FIG. 11) a metal channel frame 195' to which is attached spaced metal or wooden joists 201'. A wooden plywood sub-floor 197 is attached to joists 201' and its undersurface is coated with a layer 198 of plastic insulating foam. The bottom of the channel frame member 195' (when in erected position) is anchored to pilings 158 by means of an embedded J-bolt 162. Wall board 193 does not completely cover the lower area of the wall, and a snap-on baseboard 199 covers the area and serves as the outlet means for electrical wiring, and the like, led from harnesses mounted inside wall 52.

Already-erected on floor base 51 is an inner wall 55 of the utility section. This comprises spaced load-bearing studs 192', interior wall board 193', and other features similar to wall 52.

Channel member 195" of floor base 91 of the third section is attached to channel member 195' of floor base 80 by hinge 110, and its construction is similar to

those of the other floor bases. The channel member 195" is provided with holes 202 for accommodating anchoring J-bolts.

Outer wall 93, which is attached to channel member 195" by hinge 114, is built similarly to wall 52 and it is provided with spaced load-bearing studs 192" and outer metal sheathing 190' coated on the inside with a layer 191" of plastic foam.

The manner of mounting the roof panels is outlined in FIG. 23. Roof panel 216', the end of which is disposed on one half of ridge rafter 219', is constructed similarly to the wall panels in that the outer metal sheathing 231 is attached to load-carrying members 232, on the inside of which are attached the inner wallboards 233. The outer surface of wallboard 233 is coated with a layer 234 of insulating plastic foam. A channel member 235 is attached at the ridge end of structural members 232. A similar roof panel 216" is likewise mounted on the other half of ridge rafter 219', and the two are held at the ridge by bolt 236. A ridge cap 237 is mounted over the junction of the two panels in outside sealing relation.

The other end of roof panel 216' is attached to one half of rafter 219, while one end of the lower roof panel 216 is similarly attached by screw 238 to the other half of rafter 219. Channel member 239, serving as the lower horizontal terminus of panel 216', is connected in sealed relation with a similarly-shaped member 240 which serves as the upper terminus of roof panel 216. Channel member 241 serves as the support for the lower end of panel 216 and it is attached by fastener 242 to capping channel 243 over exterior wall 174.

When completed, the 6-room house (rear view) would appear similar to that shown in FIG. 24. In this case, walls 82 and 83 of the second section 79 have been raised, making the roof for this section higher than the others. Steps 244 and 245 and crawl space walls 246 may be added at the home owner's option.

We claim:

1. A compact transportable house package designed to be conveyed by one vehicle and unloadable therefrom as a nearly-completed house on the building site, comprising:
  - a utility section comprising a first floor base and including in already erected condition on said base a long outer wall, a first and a second shorter outer wall adjoining the ends of said long outer wall and a long inner wall, the end of said long inner wall being proximate to the remaining ends of said first and said second shorter outer walls, and inner walls forming a kitchen, an adjacent bathroom and an additional room adjacent the bathroom said inner walls being connected to said long outer wall and said long inner wall,
  - a second floor base of a second section and including in already erected condition on said second floor base a long wall and a first and a second shorter outer wall adjoining the ends of said long outer wall,
  - a vertical opening disposed between one end of said long inner wall of said utility section and said first shorter outer wall thereof said vertical opening being sufficiently wide to allow access therethrough of said first shorter outer wall of said second section,
  - said second section being disposed in nested relation with respect to said utility section with said first

shorter outer wall of the utility section disposed proximate to but, in horizontally displaced relation with the first shorter outer wall of said second section and said second outer wall of the utility section disposed proximate to but in horizontally displaced relation with the second shorter outer wall of said second section and

other building elements required for the completion of the structure of said house being disposed in and over said utility section.

2. A compact transportable house package, according to claim 1, wherein the inner edge of said first floor base is connected in hinged relation to the wall-free long edge of the second floor base.

3. A compact transportable house package, according to claim 1,

wherein:

said floor base of said utility section has two long edges and two shorter edges and said floor base of said second section also has two long edges and two shorter edges, and the long free edge of said latter base is disposed in abutting relation to the long inner edge of said first floor base, and said second section is disposed in relation to said utility section as follows:

said second floor base is disposed in overlying relation with respect to said long inner wall of said utility section,

said first shorter outer wall of the utility section disposed proximate to but, in horizontally displaced relation with the first shorter outer wall of said second section and said second outer wall of the utility section disposed proximate to but in horizontally displaced relation with the second shorter outer wall of said second section and

said long wall of said second section is disposed on top of said utility section.

4. A compact transportable house package, according to claim 3, wherein the shorter edges of said second floor base extend beyond the shorter edges of said first floor base.

5. A compact transportable house package, according to claim 1, wherein a third floor base of a third section is disposed in overlying relation over said long wall of said second section.

6. A compact transportable house package, according to claim 5, wherein a long wall, attachable to the other long edge of said third floor base, is disposed on said package.

7. A compact transportable house package, according to claim 6, in which a long wall is attached at its base, in hinged relation, at the other long edge of said third floor base.

8. A compact transportable house package, according to claim 1, and including a vehicle disposed thereunder, said package serving as a load for said vehicle.

9. A transportable house package, according to claim 8, and including a hoist disposed on the vehicle and transported therewith, said hoist being powered from said vehicle.

10. A compact transportable house package, according to claim 3, wherein said first floor base is attached in hinged relation to said second floor base.

11. A compact transportable house package designed to be conveyed by one vehicle and unloadable there-

from as a nearly-completed house on the building site, comprising:

a utility section comprising a first floor base having two long edges and two shorter edges and including, in already-erected condition on said base, a long outer wall disposed at one of the long floor edges, a long inner wall disposed at the other long floor edge, two shorter outer walls at the shorter floor edges, and inner walls forming a kitchen, an adjacent bathroom and an additional room adjacent the bathroom, and including necessary utilities,

a second floor base of a second section also having two long edges and two shorter edges and disposed with one long edge in abutting relation to the long inner edge of said first floor base and having one shorter edge extending inwardly beyond one shorter edge of said first floor base and having the other shorter edge extending outwardly beyond the other short edge of said first floor base, and including, in already-erected condition on said second base, a long wall disposed at the other long floor edge and two shorter outer walls at the shorter floor edges,

a vertical opening disposed near one end of said long inner wall of said utility section and in line with said inwardly-extending edge of said second floor base and with dimensions adequate to allow access therein of a short wall of said second section, said second section being disposed in relation to said utility section, as follows:

the second floor base is disposed in overlying relation with respect to said long inner wall of said utility section,

one of said shorter walls of the second section is disposed on its side edge through said opening and lying on said first floor base in overlying relation with respect to a shorter side of said utility section, while the other shorter side of said second section is disposed similarly on its side edge outside of the house in overlying relation with respect to the other shorter side of the utility section, and

said long wall of said second section is disposed on top of the utility section, and

other building elements needed to complete the structure of the house are disposed in and over said utility section.

12. A compact transportable house package, according to claim 11, including a vehicle disposed thereunder, said package serving as a load for said vehicle.

13. A compact transportable house package, according to claim 11, wherein said first floor base is attached in hinged relation to said second floor base.

14. A compact transportable house package, according to claim 13, including:

a third floor base of a third section also having two long edges and two shorter edges and attached at one of its long edges, in hinged relation, to the other long edge of said second floor base and disposed on top of the inner wall of said second section.

15. A compact transportable house package, according to claim 14, including a long outer wall attached at its base, in hinged relation, to the other long edge of said third floor base.

16. A compact transportable house package designed to be conveyed by one vehicle and unloadable there-

from as a nearly-completed house on the building site, comprising:

a utility section comprising a first floor base having two long edges and two shorter edges and including, in already-erected condition on said base, a 5 long outer wall disposed at one of the long floor edges, a long inner wall disposed at the other long floor edge, two shorter outer walls at the shorter floor edges, and inner walls forming a kitchen, an adjacent bathroom, and an additional room adjacent the bathroom, and including necessary utilities therefor,

a second floor base of a second section also having two long edges and two shorter edges and disposed with its one long edge in abutting relation to the 15 inner long edge of said first floor base and having one shorter edge extending inwardly beyond one shorter edge of said first floor base and having the other shorter edge extending outwardly beyond the other shorter edge of said first floor base and including, in already-erected condition on said second base, a long wall disposed at the other long floor edge, and two shorter outer walls at the shorter floor edges,

a vertical opening disposed near one end of said long 25 inner wall of said utility section in line with said inwardly-extending edge of said second floor base and with dimensions adequate to allow access therein of a short wall of said second section in a manner such that when the second floor base is 30 raised to be in overlying relation with said long inner wall of said utility section, a short wall of said second section will enter through said opening and be disposed on its side edge over the first floor base while the other short wall of said second section 35 will be similarly disposed with respect to the other short wall of said utility section outside of the house.

17. A compact transportable house package according to claim 1 designed to be conveyed by one vehicle 40 and unloadable therefrom as a nearly-completed house on the building site, comprising:

a utility section comprising a first floor base having a first and a second long edge and a first and a second shorter edge and including, in already-erected condition on said base, a long outer wall at said first long floor edge, a first and a second shorter outer wall adjoining the ends of said long outer wall located at said first and said second shorter edges respectively, and a long inner wall located at said second long floor edge, the ends of said long inner wall being proximate to the remaining ends of said first and said second shorter outer walls, and inner walls forming a kitchen, an adjacent bathroom and an additional room adjacent the bathroom and including necessary utilities, said inner walls being connected to said long outer wall and said long inner wall,

a second floor base of a second section also having a first and a second long edge and a first and a second short edge and having said first long edge attached, in hinged relation, to said second long edge of the first floor base and including, in already-erected condition on said second base, a long wall at its second long floor edge and a first and a second shorter outer walls at the said first and second shorter floor edges, and

said second section being disposed with respect to the utility section in a manner such that when the outer edge of said second base is raised so that it is in overlying relation with respect to said long inner wall of said utility section, the shorter walls of the second floor base will lie on their side edges with said first shorter outer wall of the utility section disposed proximate to but, in horizontally displaced relation with the first shorter outer wall of said second section and said second outer wall of the utility section disposed proximate to but in horizontally displaced relation with the second shorter outer wall of said second section and said long wall of said second section being disposed on top of said utility section.
